UNITED STATES PATENT OFFICE.

JESSE F. WENTZ, OF NEW YORK, N. Y., ASSIGNOR TO WESTERN ELECTRIC COMPANY, INCORPORATED, OF NEW YORK, N. Y., A CORPORATION OF NEW YORK.

ELECTRIC FUSE.

Application filed April 27, 1922. Serial No. 556,892.

This invention relates to electric fuses.

An object of the invention is to provide a filling material for fuses which will offer a maximum resistance to the tendency of the fuses to maintain an arc or to explode when the fuse conductor is disrupted.

An efficient filling material must be of a solid nature so that it can be readily used in commercial fuses; and it must have a high melting point. It must not give off a vapor which may become ionized. It must not only be a non-conductor of electricity when cool, but must maintain its non-conductive properties even when raised to a high temperature. Furthermore, the filler must be able in the shortest possible time to draw the heat away from the immediate vicinity of the break. To accomplish this, a filler must not only be a good thermal conductor, but must have a high specific heat and a high density so that it will absorb a maximum quantity of heat. The material must be compact and homogeneous in order to make the full use of its thermal conductivity; and it must be composed of granules of sufficient size so as to present a maximum surface to the gas and thus to absorb as much heat as possible.

Pursuant with its object, this invention provides the use of a fuse-filling material

composed of granules of fused quartz or other form of pure silica. Such granules, especially those ranging from 1/20 to 1/4 of an inch in diameter, possess in an unusually high degree the qualities necessary for a fuse-filling material, and have been found unusually effective in preventing arcing or explosion.

The drawing shows a fuse comprising a fuse conductor 1 and a casing 2. Granules 3 of fused quartz are shown within the casing surrounding the fuse conductor.

The invention claimed is:

1. An electric fuse having its fusible element surrounded by coarse granules of pure silica of such size that the diffusion of gas due to the melting of the fusible element is freely permitted.

2. An electric fuse having its fusible element surrounded by coarse granules of fused quartz of such size that the diffusion of gas due to the melting of the fusible element is freely permitted.

3. An electric fuse having its fuse conductor surrounded by granules of fused quartz, having a diameter of from 1/20 to 1/4 of an inch.

In witness whereof, I hereunto subscribe my name this 24th day of April, A. D. 1922.

JESSE F. WENTZ.
